CHARCOAL GRILL

Edwin P. Sundholm, Albert City, Iowa

Filed Mar. 5, 1964, Ser. No. 78,882

Term of patent 14 years

(Cl. D81—10)

FIG. 1

FIG. 2

FIG. 3

FIG. 4

Fig. 5

FIG. 1 is a side elevational view of a charcoal grill embodying my new design, the opposite side being the same;

FIG. 2 is an end elevational view thereof, the opposite side being the same;

FIG. 3 is a top plan view thereof;

FIG. 4 is a bottom view thereof; and

FIG. 5 is a perspective view thereof.

I claim:

The ornamental design for a charcoal grill, as shown and described.
